DEVICE FOR RECEIVING AND EXTINGUISHING LIGHTED CIGARETTES

Filed Nov. 28, 1950

UNITED STATES PATENT OFFICE

2,613,677

DEVICE FOR RECEIVING AND EXTINGUISHING LIGHTED CIGARETTES

Bernard S. Hawhurst, Zanesville, Ohio

Application November 28, 1950, Serial No. 197,859

2 Claims. (Cl. 131—235)

1

This invention relates to ash receivers, and more particularly to a device for receiving and extinguishing lighted cigarettes or the like.

An object of this invention is to provide a device for receiving and extinguishing lighted cigarettes which may be manually actuated from time to time to drop the extinguished cigarettes in the tray of the device without further handling of the cigarettes.

Another object of this invention is to provide a device for receiving and extinguishing cigarettes including cigarette-receiving and extinguishing cups which are movable into a position wherein the extinguished cigarettes are automatically dumped into the ash tray of the device.

A further object of this invention is to provide a device adapted to receive and extinguish lighted cigarettes and the like in a manner minimizing the occurrence of fires due to partially extinguished cigarettes.

A still further object of this invention is to provide a device for receiving and extinguishing lighted cigarettes and the like, which is relatively simple in structure and cheap to manufacture.

A still further object of this invention is to provide a device for receiving and extinguishing cigarettes which is adaptable for use as a table or desk-type ash receptacle, or a pedestal or stand-type ash receptacle.

The above and still further objects and advantages of the present invention will become apparent upon consideration of the following detailed description of the invention, when taken in conjunction with the accompanying drawings, wherein:

Figure 1 is a side elevational view, with parts broken away and shown in section, of the cigarette-receiving and extinguishing device of the present invention;

Figure 2 is a top plan view, with parts broken away, of the cigarette-receiving and extinguishing device shown in Figure 1;

Figure 3 is a fragmentary sectional view taken substantially along the line 3—3 of Figure 1;

Figure 4 is a fragmentary side elevational view of a modified form of the cigarette-receiving and extinguishing device of the present invention;

Figure 5 is a perspective view of the cigarette-receiving and extinguishing cup constructed according to the present invention; and

Figure 6 is a fragmentary perspective view of the intermediate portion of a handle similar to that of Figure 1, but having only one cigarette-receiving and extinguishing cup constructed ac-

2

cording to the present invention attached thereto.

Referring now more particularly to the drawings, wherein like reference numerals have been used throughout the several views to designate like parts, there is shown the cigarette-receiving and extinguishing device of the present invention, generally designated by the reference numeral 10, which includes an upstanding tray 11 having a base 12, upstanding end walls 13 and 14 and upstanding side walls 15 and 16. The base 12, the end walls 13 and 14 and the side walls 15 and 16 cooperate to define the ash tray 11 having the open top 17.

Spaced above the open top 17 of the ash tray 11 is a horizontally disposed handle 18 which is supported longitudinally of and intermediate the sides of the tray 11 by means of the depending legs 19 and 20. Contiguous to each of its ends the handle 18 is provided with the transversely extending cigarette-supporting notches 22 and 23.

The handle 18 is cut away intermediate its ends to form a longitudinally extending seat 24, the ends of the seat 24 being defined by the spaced shoulders 25 and 26. Disposed longitudinally of the seat is a base piece 27 which is supported on the seat 24 by means of the nut-and-bolt assembly 28 which extends transversely under and adjacent to the base piece 27 and holds the latter in its supported position on the seat 24 intermediate the spaced shoulders 25 and 26. The base piece 27, Figure 3, has upwardly projecting sides 27a and 27b inclined toward each other.

Disposed on one side of the handle 18 is a cigarette-extinguishing cup 30 which is mounted on the base piece 27 for rocking movement about a horizontal axis from a normal upwardly inclined cigarette-receiving position abutting against one of the sides or side 27a of the base piece 27 to a downwardly inclined cigarette dumping position abutting against the other of the sides or side 27b of the base piece 27 and facing the interior of the tray 11, the abutment of the cup 30 with the side 27b limiting the rocking movement of said cup and causing ejection of the extinguished cigarette butt therefrom. The cigarette-receiving position of the cup 30 is clearly shown in the full lines in Figure 3, while the cigarette-dumping position is clearly illustrated by the broken lines in Figure 3.

Disposed on the other side and spaced from the cup 30 is a cup 31 which is likewise mounted on the base piece 27 for rocking movement about

a horizontal axis from a normally upwardly inclined cigarette-receiving position abutting against the other of the sides or side 27b of the base piece 27 to a downwardly inclined cigarette dumping position abutting against the one of the sides or side 27a of the base piece 27 and facing the interior of the tray 11, the abutment of the cup 31 with the side 27a of the base piece 27 limiting the rocking movement of said cup and causing ejection of the extinguished cigarette butt therefrom. Each of the cigarette-receiving and extinguishing cups 30 and 31 is provided with an elongated cigarette-receiving bore 32 and 33, each of the bores being tapered inwardly from the open mouth of the cup toward the bottom thereof. As clearly shown in Figure 3, the lowermost end of the cigarette-receiving bore is of a diameter substantially equal to the diameter of the cigarette and accordingly cooperates with the cigarette to extinguish the latter due to oxygen deprivation. It is to be noted that the exterior of the cups may be formed in any desired shape, and the exposed surfaces thereof suitably ornamented. This arrangement of the cups 30 and 31 being longitudinally spaced from each other and separated by the handle 18 extending therebetween enables a more even distribution of the extinguished butts on the floor 12 of the tray 11 on both sides of the handle 18, and also, makes an extinguishing cup available to smokers who may happen to be on the opposite sides of the tray.

The structural arrangement of the cigarette-receiving and extinguishing device illustrated in Figures 1 to 3, inclusive, is particularly adapted for a construction employing a relatively fragile material, such as glass or a ceramic material, in the fabrication of the ash tray 11, the handle 18, the depending legs 19 and 20. In Figure 5 there is shown one of the cups 30 which includes the body 35 fabricated of a sturdy material, and the supporting bracket 36 fabricated of a relatively sturdy material, the supporting bracket 36 being secured transversely of and in abutting engagement with the outer periphery of the cup 30 by means of the rivet 37. The bracket 36 includes the spaced, opposed ears 38 and 39 which are suitably apertured for the extension therethrough of a pivot bolt 40, Figure 3. The base piece 27 is fabricated of a sturdy material and includes bolt-receiving sleeves 41, 42 and 43 disposed in end-to-end spaced relation with respect to each other. The bracket 36 of the cup 30 is received in the space between the sleeves 41 and 42 and supported on the bolt 40, while the bracket of the cup 31 is received in the space between the sleeves 42 and 43 and likewise supported on the pivot bolt 40.

In Figure 4 there is shown a modified form of the cigarette-receiving and extinguishing device of the present invention in which the entire device is fabricated of a relatively sturdy material, enabling the pivotal supports to be formed integrally with or secured to the cups and the pivot sleeves secured to or formed integrally with the handle. The handle 18, Figure 4, has formed integrally therewith or secured thereto the spaced sleeves 50, 51 and 52 which are disposed in end-to-end aligned relation with respect to each other. Mounted contiguous to one side of the handle 18 is the cup 53 which is pivotally supported by means of the bolts 55 and the spaced ears 56 and 57 for movement similar to the rocking movement of the cup 30. Another cup 58 is disposed in side-by-side, spaced relation with respect to the cup 53 and likewise pivotally mount-

ed by means of the spaced ears 59 and 60 on the bolt 55 for movement in the manner previously described in connection with the cup 31.

The cigarette-receiving and extinguishing device is obviously not limited to use as a table or desk model or type of ash receptacle, as illustrated in Figures 1 to 5 of the drawings, but can be used in the pedestal or stand-type ash receptacles.

intermediate portion of a handle 65 of the same structure as handle 18 of the form of Figures 1 to 3 inclusive on which is supported a cigarette-extinguishing cup 66 constructed according to the present invention. The cup 66 includes spaced ears 67 and 68 and is supported by means of a base piece 69 which is detachably secured to the handle 65 by a nut-and-bolt assembly 70 which is of the same type as that designated by the numeral 28 in the form of Figures 1 to 3. The base piece includes a pair of bolt-receiving sleeves 71 and 72 which are disposed in end-to-end spaced relation with respect to each other and receive therebetween the spaced ears 67 and 68 of the cigarette-extinguishing cup 66. Extending through the bolt-receiving sleeves 71 and 72 and apertures provided in the ears 67 and 68 is a bolt 73 which mounts the cup 66 for rocking movement from a normally upwardly inclined cigarette-receiving position contiguous to and abutting against one side of the base piece 69 toward the inclined cigarette-dumping position overlying the base piece 69 and facing toward the tray 11.

From the foregoing it is readily apparent that numerous modifications can be made without departing from the spirit of the invention as set forth in the appended claims.

What I claim is:

1. A device for receiving and extinguishing cigarettes and the like comprising an upstanding tray having an open top, a horizontally disposed handle traversing the center of and spaced above the open top of said tray and supported on the open top of said tray, a base piece having upwardly projecting sides inclined toward each other positioned on said handle and carried thereby for attachment of cigarette extinguishing cups thereto, a first cigarette extinguishing cup disposed on one side of and spaced radially inwardly of one end of said base piece and mounted on said base piece for limited rocking movement about a horizontal axis from a normal upwardly inclined cigarette receiving position abutting against one of the sides of said base piece to a downwardly inclined cigarette dumping position abutting against the other of the sides of said base piece and facing the interior of said tray, said rocking movement being limited by the abutment of said cup with the other of the sides of said base piece, and a second cigarette extinguishing cup disposed on the other side of and spaced radially inwardly of the other end of said base piece and mounted on said base piece for limited rocking movement about a horizontal axis from a normal upstanding inclined cigarette receiving position abutting against the other of the sides of said base piece to a downwardly inclined cigarette dumping position abutting against the one of the sides of said base piece and facing the interior of said tray, said second cup being oppositely spaced from said first cup, whereby to dispose of extinguished butts on opposite sides of the handle to provide an even distribution thereof on the tray bottom.

2. A device for receiving and extinguishing cigarettes and the like comprising an upstanding tray having an open top, a horizontally disposed handle traversing the center of and spaced above the open top of said tray and supported on the open top of said tray, a base piece having upwardly projecting sides inclined toward each other positioned on said handle and carried thereby for attachment of cigarette extinguishing cups thereto, a first cigarette extinguishing cup disposed on one side of and spaced radially inwardly of one end of said base piece and mounted on said base piece for limited rocking movement about a horizontal axis from a normal upwardly inclined cigarette receiving position abutting against one of the sides of said base piece to a downwardly inclined cigarette dumping position abutting against the other of the sides of said base piece and facing the interior of said tray, said rocking movement being limited by the abutment of said cup with the other of the sides of said base piece, and a second cigarette extinguishing cup disposed on the other side of and spaced radially inwardly of the other end of said base piece and mounted on said base piece for limited rocking movement about a horizontal axis from a normal upstanding inclined cigarette receiving position abutting against the other of the sides of said base piece

to a downwardly inclined cigarette dumping position abutting against one of the sides of said base piece and facing the interior of said tray, said second cup being oppositely spaced from said first cup, each of said cigarette receiving cups being provided with an elongated cigarette receiving bore tapering inwardly from the open mouth of said cup toward the bottom thereof, whereby to dispose of extinguished butts on opposite sides of the handle to provide an even distribution thereof on the tray bottom.
